(57) **CLAIM**

The ornamental design for a handheld food product analyzer, as shown and described.

DESCRIPTION

FIG. 1 is a front upper right perspective view of a handheld food product analyzer showing the new design; and

FIG. 2 is a rear lower left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines represent portions of the article that form no part of the claimed design.
